AUTOMATIC AMPLITUDE CONTROL OF
SPEECH SOUND WAVES
Meguer V. Kalfaian, 962 Hyperion Ave.,
Los Angeles 29, Calif.
Filed Nov. 10, 1958, Ser. No. 773,065
1 Claim. (Cl. 330—131)

This invention relates to automatic amplitude control systems, and particularly to a system for normalizing the amplitude of propagated speech sound waves to a constant-peak amplitude level. Its main object is to transform an incoming speech sound wave having wide variation in amplitude into an outgoing speech sound wave having a uniform amplitude level, without loss of intelligibility and with minimum sacrifice in quality.

In various forms of speech sound wave production and reproduction, it is often desired that the wide variations of amplitude in speech sound waves, as originated in the vocal system, are synthetically reduced to a standard peak amplitude. Such standardization of peak amplitude will effect loss of voice quality, but the intelligibility will be preserved, and accordingly, the said modified speech sound waves may be utilized for transmission through various forms of transmission links where the signal-to-noise ratio is very low. In ordinary transmission through such low signal-to-noise ratio link, the transmission of the phonetic sound "a" may be received intelligibly, because of its inherent high amplitude, but the phonetic sounds, such as, "v" or "s," may be completely lost in noise, because of their inherent weaknesses in amplitude. In another form of speech sound wave reproduction, peak-amplitude standardization is desirable for the analysis of amplitude ratios between various resonances in different phonetic sounds of the speech, for example, in the system as disclosed in my patent application, Serial Number 723,510, filed March 24, 1958, now Patent No. 2,921,133. Ordinary methods and systems of amplitude control, as practiced in the art of electronics, however, are not adequate for the particular purpose contemplated herein, as they are not capable of following the sudden changes in amplitude from one phonetic sound to another. As each phonetic sound comprises repetitive wave trains, and the peak amplitude of these wave trains varies widely, both by reason of the inherent characteristics of the vocal system, and by environmental changes, the object of the present invention is, accordingly, to provide an amplitude control system which shifts the peak-amplitude of the propagated speech sound waves to a standard level in stepwise shifts train after train. In its broader aspects, the fundamental frequencies of the propagated speech sound waves are first selected; narrow pulses are produced at these fundamental frequencies; and these narrow pulses are used to drive the amplitude-control system. The nature of such a system will be apparent from the following specification, and in connection with the accompanying schematic arrangements, wherein, FIG. 1 is a schematic diagram of the system embodying the invention; FIG. 2 is a series of waveforms illustrating the operation of the invention; and FIG. 3 is a block diagram illustrating the principles of the invention.

In ordinary speech, each phonetic sound consists of a train of substantially replica waves, formed by fairly regular puffs of air from the glottis, which are set into vibrations in the momentarily formed resonant cavities of the vocal system. As each puff of air enters these cavities, an initial surge of pressure is formed, and accordingly, these vibrations are commenced by a high peaked wave; the series of occurrences of which determine the fundamental (pitch) frequencies of the speech sound wave at any given period of time. It is then possible

2

to select these high peaked waves, or, major peaks, as named in the present disclosure, and produce at these peak periods marker pulses. A detailed description on systems for selecting these major peaks, and producing 5 marker pulses thereat, may be referred to a disclosure in my U.S. Patent No. 2,673,893, March 30, 1954. A section of several wave trains (just mentioned) is illustrated at A in FIG. 2. The major peaks of these wave trains are indicated by the numerals 1 through 3 in the drawing. It 10 will be noted that the amplitudes of wave trains *a* and *b* may be different than the amplitude of wave *c*. The purpose herein contemplated is, accordingly, to change the amplitudes of these wave trains, in a manner that, the 15 major peaks have constant reference amplitudes, without distorting the original wave form; thus keeping distortion in quality of the original speech sound wave at a minimum. This is accomplished by passing the original sound wave through a gain controllable amplifier, the gain of which is shifted stepwise at said major peaks, such 20 as shown by the square waves at D of FIG. 2. These gain shifting points are abrupt, but in practice, a lag of substantially short pulse period is sufficient to obviate any distortion effects upon the gain-controlled sound wave. Such a short pulse is shown at C of the drawing in FIG. 2, 25 which causes pulse waves 4 to appear upon the gain-controlled trains of waves at B. Due to the high frequency characteristics of these pulses, however, they can be easily eliminated in an outgoing circuit having a band pass width of only covering the spectrum band of the original speech 30 sound waves, in a conventional mode.

The system actually used is described by way of a block diagram, as shown in FIG. 3, wherein, the original speech sound wave is produced in block 5. The output of block 5 is applied to the input of a gain controllable amplifier 6, and a major peak selector block 7. The output of the gain controllable amplifier block 6 is fed back to its input in degenerative mode by way of a unidirectional storage device, for example, a rectifier and a capacitor connected in series, in block 8. This storage device is reference 35 biased by way of block 9, in such a manner that, the storage device 8 is energized only when the magnitude of amplified wave of block 6 exceeds in magnitude of the reference bias in block 9. Thus, the peak amplitude of amplified wave of block 6 is substantially equal to the reference magnitude of bias in block 9. The storage device in block 8 is normally non-dischargeable, and accordingly, after it has been charged to a controlling value, it holds the gain of amplifier block 6 in steady state. A 40 normally inoperative discharger element in block 10 is provided. The major peak selector in block 7 produces a pulse signal in block 11, at the arrival of a major peak, and this pulse signal is applied to the discharger in block 10, for momentarily discharging the storage device in block 8, so that it may recharge to a new level for the 45 control of amplifier block 6. Thus the input of amplifier in block 6 sees the original wave at A in FIG. 2, and the output of said amplifier is transformed into a wave having uniform amplitude of major peaks, as shown at B in 50 FIG. 2.

Having described the broader aspects of the present invention, detailed specification is now made by way of the schematic arrangement in FIG. 1, which consists of five dual control tubes V1 to V5, and four phase inverter tube V6 to V9. The dual control tubes V1 to 55 V5 are of the type having two separate control grids, either one of which is capable of controlling the grain of the tube. Thus, the speech sound waves are applied to one of the control grids, for example, the first grid G1, of dual control tube V1. The control grid G1 of V1 is normally biased through load resistor R1 (as indicated in the drawing) to a conductive point of the tube,

so that the voltage variations of the speech sound waves appearing at grid G1 are transmitted faithfully to the anode circuit resistor R2. These corresponding voltage variations across R2 are produced in reversed polarity with respect to the voltage variations appearing at control grid G1. Accordingly, the voltage variations across R2 are coupled to the control grid of phase inverter tube V6, through coupling capacitor C1, so that these latter voltage variations are now transmitted to the anode circuit resistor R3 of V2, in phase polarity corresponding to the phase polarity of the voltage variations appearing at the control grid G1 of the dual control tube V1. This process is repeated through several stages comprising dual control tubes V2 to V5, and intermediate phase inverter stages comprising tubes V6 to V9, so that the first control grids G1 of dual control tubes V1 to V5 receive the voltage variations of the speech sound wave in the same polarity. The first control grids G1 of dual control tubes V2 to V5 are biased through load resistors R4 to R7, respectively; the control grids of phase inverter tubes V6 to V9 are biased through load resistors R8 to R11, respectively; the anode circuit resistors of dual control tubes V2 to V5 are designated as R12 to R15, respectively; the anode circuit resistors of phase inverter tubes V7 to V9 are designated as R16 to R18, respectively; and the coupling capacitors from stage to stage of alternate dual control and phase inverter tubes V1 to V9 are designated as C1 to C8.

Continuing with the function of dual control tube V1 and the phase inverter tube V6, it was stated that each time the voltage variations of the speech sound wave are applied upon the first control grid of a dual control tube, for example, V1, these voltage variations are transmitted to the anode circuit of that tube in phase inverted polarity. Also, by applying these phase inverted voltage variations to the control grid of an intermediate stage, for example, tube V6, the original polarity of said voltage variations is reinstated in the anode circuit resistor, for example, resistor R3. Thus by the use of intermediate phase inverter stages, the first control grids G1 of the dual control tubes V1 to V5 see the voltage variations of the speech sound waves in the same polarity.

The voltage variations of the speech sound waves in the anode circuit resistor R15 of the last dual control tube V5 are coupled to the control grid of cathode follower tube V10, through coupling capacitor C9. The voltage variations developed across load resistor R21 are charged in storage capacitor C12 through series connected diode D1. The closed circuit loop of storage capacitor C12; the diode D1; and load resistor R21, however, is made in series with a reference bias voltage of source B1, the magnitude of the later of which determines the peak-amplitude of the speech sound waves to be standardized. The diode D1 is so polarized that only signals of negative potential developed across load resistor R21 is transmitted to be charged in storage capacitor C12. Also, the reference bias potential of B1 is so polarized that, the negative signal potential developed in the load resistor R21 does not pass through the diode D1 until the amplitude of said negative potential is higher than the potential of B1. Thus, the storage in capacitor C12 remains constant until a negative potential of higher amplitude than the potential of B1 is developed in the load resistor R21, at which point the capacitor C12 becomes negatively charged and reduces simultaneously the gain of dual control tubes V1 to V5; by virtue of the fact that the capacitor C12 is connected in parallel to the second control grids G2 of these tubes. During the charging period of capacitor C12 (in negative polarity), the gain of the dual control tubes decreases, and accordingly, the amplitude of the instantaneous signal voltage across load resistor R21 is reduced to a level equal to, or below the voltage of B1, where the capacitor C12 can no longer be charged, and therefore, the charge of capacitor C12 remains constant thereafter, determining

the standard amplitude level of the speech sound waves at a suitable output terminal, for example, taken from across the anode circuit resistor R15 of dual control tube V5.

In accordance with the characteristic nature of the fundamental frequencies of speech sound waves, as described in the foregoing by way of the graphic illustration in FIG. 2, and the block diagram in FIG. 3, it is then only necessary to produce narrow pulses at the major peaks (fundamental frequencies) of the propagated speech sound waves, and discharge the storage capacitor C12 during these narrow pulse periods, so that the gains of dual control tubes V1 to V5 may be shifted step-wise from major peak to major peak. The discharge of storage capacitor C12 is achieved by the discharger tube V11, which is connected electrically in parallel with the capacitor C12. This latter tube, however, is normally rendered non-conductive by a high negative bias upon its control grid, as indicated in the drawing. The marker pulses at fundamental frequencies are applied upon the control grid of discharger tube V11 in positive polarity, so that the tube V11 becomes conductive at these short pulse time periods, discharging the capacitor from its previous storage. This discharge, however, is not complete, as during the discharge period the voltage across the load resistor R21 is at a new amplitude level, and the voltage across capacitor C12 assumes this amplitude level immediately after the discharging pulse has ceased to zero value. Thus, the gains of all dual control tubes V1 to V5 are varied in steady state steps at the repetition rate of said fundamental frequencies, and the amplitude of the original speech sound waves is shifted to a standard level, where all said major peaks have the same height.

Referring again to the modulator tubes V1 to V5, it is essential that during gain shifting period the first control grids G1 of these tubes are impressed upon by signal voltages of like polarity, so that the gain of one tube will not offset the gain of another tube. For this reason, the phase inverter stages comprising tubes V6 to V9 are included intermediate to the dual control tubes. In reference to the phase inverter and cathode follower tube V10, this latter tube may be eliminated in conjunction with the component parts comprising resistors R19, R23 and C10, by connecting the coupling capacitor C9 from the anode circuit of dual control tube V5 to the resistor R21. In this case; the function of the arrangement would be the same as described previously, e.g., the gains of dual control tubes V1 to V5 being shifted during said narrow pulses produced at said major peaks.

It will be noted in the arrangement of FIG. 1, that, a single dual control tube will suffice for the purpose contemplated herein. The reason that five dual control tubes (V1-V5) are used in the arrangement, to perform the function of a single dual control tube, is to reduce the burden imposed on each tube, and thereby reduce nonlinear distortion of the original sound wave. Since nonlinear parts will inherently distort the admitted waveform, regardless how small it may be, the phase inverter tubes V6 to V9 are chosen of the pentode type, so that they may offer opposing nonlinearity and cancel out most of the distortion present. Of course, triode phase inverters may also be used, if so desired. Also, any number of dual control stages may be used, according to the particular use and requirements involved.

When the controlled amplitude of the speech sound wave is to be made at a highly amplified level, then the signal voltage developed across plate circuit resistor R15 of dual control tube V5 may be first amplified across an impedance means, and a fractional tap taken therefrom to be coupled to the control grid of tube V10. The first control grids G1 of dual control tubes V1 to V5, and the control grids of phase inverter tubes V6 to V9 are shown connected in parallel to a common bias source. Such connection is shown for convenience, however, and the biases on different tubes may vary, if so desired,

without affecting the function of the arrangement. The circuit arrangement in FIG. 1 is not limited to vacuum tubes, as transistors may also be utilized to obtain similar performance. The tetrode transistors, available commercially, are examples in substitution of said dual control tubes.

What I claim is:

In complex waves having contiguous wave trains of random amplitudes, the beginning and ending of each wave train being determined by major peaks of the complex wave, the system of equalizing the amplitudes of these wave trains stepwise in steady states comprising means for producing said complex waves; a major peak selector; means for applying the produced complex waves to said selector for producing pulse waves at said major peaks; a gain controllable amplifier having first and second inputs and an output; means for applying the produced complex waves to the first input of said amplifier, for amplifying same at said output; a series connected circuit comprising a reference bias source, a rectifier means, and a capacitor means; means for applying said

amplified output waves to last said circuit for rectifying same and charging said capacitor by the rectified waves proportionally when larger in magnitude than said bias source; means for coupling the charge of said capacitor to said second input in gain reducing direction, thereby reducing the gain of said amplifier to a point where the peak of the amplified wave train is substantially equal to that of the reference bias; a normally inoperative discharger means in parallel with said capacitor; and means for applying said pulse waves upon said discharger means for momentarily discharging the capacitor, and thereby resetting for the said steady state gains of the amplifier.
